COMBINED LAMP PROJECTOR AND SCREEN FOR PRODUCING VARIABLE LUMINOUS IMAGES

Nicolas Schöffer, Paris, France, assignor, by mesne assignments, to U.S. Philips Corporation, New York, N.Y., a corporation of Delaware

Filed Nov. 4, 1968, Ser. No. 14,444

Term of patent 14 years

Claims priority, application France May 10, 1968

Int. Cl. D26—02

U.S. Cl. D48—20

Fig. 1

Fig. 2

Fig. 3

Fig. 4

FIG. 1 is a side perspective view of the combined lamp projector and screen for producing variable luminous images,

FIG. 2 is a front view thereof,

FIG. 3 is a top plan view thereof, and

FIG. 4 is a bottom plan view thereof.

The side of the apparatus not shown is substantially the same as the side shown.

I claim:

The ornamental design for combined lamp projector and screen for producing variable luminous images, as shown and described.
